UNITED STATES PATENT OFFICE.

OTTO S. SCHAIRER, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

ELECTRICAL REGULATOR.

1,147,688.

Specification of Letters Patent. Patented July 20, 1915.

Application filed October 5, 1911, Serial No. 652,897. Renewed April 14, 1915. Serial No. 21,452.

To all whom it may concern:

Be it known that I, OTTO S. SCHAIRER, a citizen of the United States, and a resident of Edgewood Park, in the county of Allegheny and State of Pennsylvania, have invented a new and useful Improvement in Electrical Regulators, of which the following is a specification.

My invention relates to electrical regulators, and it has for its object to provide a simple and exceptionally effective regulator of the kind in which the regulation is effected by adjustment of the field excitation of a dynamo-electric machine.

Figure 1 of the accompanying drawing diagrammatically illustrates a system embodying my invention, and Fig. 2 similarly illustrates a system embodying a modification of the regulator of Fig. 1.

A system in connection with which the present invention may be conveniently employed comprises an alternating current generator the armature 1 of which is connected to a suitable distributing circuit 2—3—4, and the field magnet winding 5 of which is supplied with exciting current from the armature 6 of an exciter. The field magnet winding 7 of the exciter is preferably shunt excited, though it may be supplied with current from any other suitable source, and in series therewith is a resistor 8, the terminals of which are respectively connected to a pair of coöperating stationary and movable terminal members 9 and 10, which constitute parts of a relay 11. The movable contact terminal 10 is normally maintained out of engagement with terminal 9 by means of a spring 12, and is drawn into engagement therewith when an actuating winding 13 for the relay is energized, the said winding being supplied with current from the exciter, or from any other suitable source.

The circuit of relay-actuating winding 13 is controlled by a pair of coöperating contact terminals 15 and 16, the terminal 15 being resiliently mounted, as, for instance, by being carried at the free extremity of a plate spring 17, the other end of the spring being clamped to a stationary post 18. The contact terminal 16 is mounted upon one end of a lever 19 that is pivoted at one end to another lever 20 having an intermediate fulcrum or pivot at 21. The contact terminal 16 is normally held in engagement

with terminal 15 by means of a spring 22, and is adapted to be moved out of engagement therewith by means of an electromagnet winding 23, having a core 24 that is secured to the lever 19, the movements of the lever 19 and attached parts being somewhat retarded by means of a dash pot 25. The winding 23 and the dash pot 25 are carried by the lever 20 so that the winding 23 may effect movements of the contact terminal 16 independently of any movements of lever 20 around its fulcrum point.

The winding 23 is supplied with current from the distributing circuit 2—3—4 through a transformer 26, and its circuit is controlled by the engagement and disengagement of a pair of coöperating stationary and movable contact terminals 27 and 28. The contact terminals 27 and 28 constitute parts of a relay 29 that is similar in construction to the relay 11 and is provided with an actuating winding 30 that is connected in parallel with the actuating winding 13 of the relay 11, so that its circuit is controlled in a similar manner.

The lever 20 is adapted to be moved upon its fulcrum point by means of an electromagnet winding 32 that is supplied with current proportional to the voltage of the circuit 2—3—4, and is provided with a core 33 that is suspended from the lever 20, the movements of core 33 and of lever 20 being preferably somewhat retarded by means of a dash pot 34. The weight of the core 33 is partially counterbalanced by means of an adjustable counterweight 35.

While the various parts of the regulator may be disposed in any other convenient or desired relation with respect to each other, I prefer the arrangement shown, in which the coil 23 is suspended from the lever 20 directly below its fulcrum point. With this arrangement no counterbalancing means for the coil 23 is necessary, and the movements of the coil are minimized with the result that its inertia becomes a relatively unimportant factor.

As the winding 32 is continuously supplied with energizing current from the circuit 2—3—4, it serves to alter the position of the lever 20, and also the distance between contact terminals 15 and 16, in accordance with variations of the voltage of the circuit 2—3—4. The winding 23 being intermittently energized, serves to move the

contact terminal 16 into and out of engagement with the terminal 15, the relation of the periods of engagement to periods of disengagement depending upon the initial distance between the contact terminals, as determined by the winding 32 in response to variations of the voltage of the circuit 2-3-4. It will be understood that variations of the periods of engagement and disengagement of the terminals 15 and 16 are permitted because the terminal member 15 is resiliently mounted.

The manner in which the regulator operates will be best understood from a somewhat detailed consideration thereof. If the voltage of the circuit 2-3-4 becomes reduced, as, for instance, because of a sudden increase of load, the winding 32 becomes less strongly energized, with the result that the contact terminal 16 is moved closer to the terminal 15. When the circuit of the winding 23 is interrupted the spring 22 serves to draw the contact terminal 16 into engagement with the terminal 15, whereupon the relay actuating winding 13 and 30 becomes energized, and the contact terminals 10 and 28 are thereby moved into engagement with the terminals 9 and 27, respectively. The engagement of terminals 9 and 10 establishes a shunt to the resistor 8, with the result that the excitation and voltage of the exciter are increased, followed by corresponding increases of the excitation and voltage of the main generator, the increase of the main generator voltage serving to compensate for the reduction of the voltage of the circuit 2-3-4, previously assumed to exist. The increase of the main generator voltage causes the winding 32 to be more strongly energized, with the result that the contact terminal 16 is raised slightly. Upon engagement of the contact terminals 27 and 28, the winding 23 becomes energized and the contact terminal 16 is moved out of engagement with the terminal 15, in opposition to the tension of the spring 22. When the contact terminals 15 and 16 are out of engagement, the relay actuating windings 13 and 30 become deenergized and the contact terminals 10 and 28 move out of engagement with the terminals 9 and 27, followed by diminutions of the voltages of the exciter and main generator and by deenergization of the winding 23.

The regulator continues to operate in this manner, the contact terminal 16 being moved into and out of engagement with terminal 15 by the winding 23, and the periods of engagement and disengagement of the said terminals being determined by the winding

32 in accordance with variations of the voltage of the distributing circuit, and in such a manner that the voltage of the said circuit will be maintained substantially uniform, and that the said voltage will be promptly restored to stability and its normal value when sudden or violent fluctuations thereof result from any cause. Since, in the regulator of Fig. 1, the coil 23 is located directly below the pivotal point of the lever 22, its movements will be substantially entirely lateral, and, consequently, the said coil may be stationarily supported, if desired, instead of being carried by the lever 20, as shown.

In the system of Fig. 2, the coil 23 is mounted upon one end of the main regulator lever 37, rather than directly below its fulcrum point, and the auxiliary lever 38 is mounted upon the same pivot pin as the lever 37, but so as to be movable independently thereof, or upon a separate pivot preferably arranged with its axis in alignment with the axis of the pivot of the lever 37, though it is not necessarily in alignment therewith. The connections and operation of the regulator of Fig. 2 are the same as of the regulator of Fig. 1.

While the regulator has been shown as adapted to effect voltage regulation only, it will be readily understood that it is not limited in its application to such specific use but may be employed, without departing from the spirit of the invention, for the regulation of any other electrical quantity, and in accordance with variations of any other desired electrical condition, by simple modifications that may be made by anyone skilled in the art.

I claim as my invention:

1. An electrical regulator comprising co-operating contact members, an electromagnetic actuator for one of said members, a lever carrying the said actuator substantially directly below its fulcrum, and an electromagnetic actuator for the lever.

2. An electrical regulator comprising co-operating contact members, a lever having a stationary fulcrum carrying one of said members, an electromagnetic actuator for the said lever, a second lever also having a stationary fulcrum and carrying the said actuator, and an electromagnetic actuator for the said second lever.

In testimony whereof, I have hereunto subscribed my name this 29th day of Sept. 1911.

OTTO S. SCHAIRER.
